(57) **CLAIM**

The ornamental design for a camera component, as shown and described.

DESCRIPTION

FIG. 1 is a front perspective view of a camera component of the present invention;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and

FIG. 8 is a bottom plan view thereof.

FIG. 9 is a front perspective view of a second embodiment of a camera component of the present invention;

FIG. 10 is a rear perspective view of the camera component of FIG. 9;

FIG. 11 is front elevational view of the camera component of FIG. 9;

FIG. 12 is a rear elevational view of the camera component of FIG. 9;

FIG. 13 is a right-side elevational view of the camera component of FIG. 9;

FIG. 14 is a left-side elevational view of the camera component of FIG. 9;

FIG. 15 is a top plan view of the camera component of FIG. 9; and,

FIG. 16 is a bottom plan view of the camera component of FIG. 9.

Phantom lining, throughout the views depicting portions of a camera component in which the design is embodied is for illustrative purposes only and form no part of the claimed design.

1 Claim, 12 Drawing Sheets
